CLAIM

The ornamental design for a cake stacking system, as shown and described.

DESCRIPTION

FIG. 1 is a perspective view of a cake stacking system showing our new design.

FIG. 2 is a side view thereof, the other side being identical.

FIG. 3 is a top plan view thereof.

FIG. 4 is a bottom plan view thereof.

FIG. 5 is a perspective view of one column, shown separately for clarity of illustration.

FIG. 6 is a side view of FIG. 5, the other side being identical.

FIG. 7 is a top plan view of FIG. 5.

FIG. 8 is a bottom plan view of FIG. 5.

FIG. 9 is a perspective view of another column, shown separately for clarity of illustration.

FIG. 10 is a side view of FIG. 9, the other side view being identical.

FIG. 11 is a top plan view of FIG. 9; and,

FIG. 12 is a bottom plan view of FIG. 9.

The broken lines are for illustrative purposes only and form no part of the claimed design. The break lines illustrated in FIGS. 5, 6, 9 and 10 are not part of the claimed design and represent that no particular length is claimed.
